(57) CLAIM

The ornamental design for a rotatable storage rack, as shown and described.

DESCRIPTION

FIG. 1 is a top perspective view of a rotatable storage rack showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a bottom perspective view thereof.

FIG. 9 is a perspective view of a rotatable storage rack by adding another rack; and,

FIG. 10 is a perspective view of a rotatable storage rack shown only one rack.

1 Claim, 10 Drawing Sheets
